CLAIM

The ornamental design for a display rack with light as shown and described.

DESCRIPTION

FIG. 1 is a rear perspective view of a display rack with light embodying my new design;

FIG. 2 is a front perspective view thereof;

FIG. 3 is a top plan view thereof, the bottom plan view being a mirror image thereof;

FIG. 4 is a front elevation view thereof; the rear elevation view being a mirror image thereof; and,

FIG. 5 is a left elevation view thereof; the right elevation view being a mirror image thereof.

The broken lines shown in FIGS. 1, 2, 4, and 5 illustrate portions of the display rack with light that form no part of the claimed design. None of the broken lines form part of the claimed design.

The claimed design is shown with a symbolic break in its length/height. The appearance of any portion of the display rack with light between the broken lines forms no part of the claim. The broken lines in the drawings depict the bounds of the claimed design and form no part of the claimed design.
